UNITED STATES PATENT OFFICE.

FRANCIS H. TOBIAS, OF NEW YORK, N. Y.

DESIGN FOR AN EASEL.

SPECIFICATION forming part of Design No. 16,511, dated February 9, 1886.

Application filed November 9, 1885. Serial No. 182,311. Term of patent 7 years.

To all whom it may concern:

Be it known that I, FRANCIS H. TOBIAS, of the city and State of New York, have invented a Design for an Easel, of which the following 5 is a specification.

This design is represented in the accompanying photographs; and it consists in a conventionalized representation of oars and of a fish-net. The converging side pieces of the 10 easel are round and slightly tapering in the upper parts, *a*, and broadened and thin in the lower parts, *b*, being a conventionalized representation of oars. The back leg, *c*, is round, and at the upper end is a hoop and hanging 15 ornamental net, *d*. The picture-supports *e*

on the side pieces, *a*, are in the shape of yokes or forks, as represented.

I claim—

The design for an easel composed of the converging side pieces, that are conventionalized 20 representations of oars, and the round back leg and ornamental hoop and net at the upper end, and the supports *e*, substantially as described and shown.

Signed by me this 5th day of November, 25 1885.

F. H. TOBIAS.
